Inventor.

John Kennedy

United States Patent Office.

JOHN KENNEDY, OF CLAVERACK, NEW YORK.

Letters Patent No. 94,218, dated August 31, 1869.

IMPROVEMENT IN STOPPING-MECHANISM FOR KNITTING-MACHINE.

The Schedule referred to in these Letters Patent and making part of the same.

Be it known that I, JOHN KENNEDY, of the town of Claverack, in the county of Columbia, and State of New York, have invented a new and useful Stop-Device or Attachment to be applied to Rotary Knitting-Machines for preventing imperfections in the cloth or fabric made, and for preserving the needles; and I do hereby declare that the following is a full, clear, and exact description of the construction and operation of the same, reference being had to the annexed drawings, making a part of this specification, in which—

Figure 1 is a perspective view of my new stop-device.

The object of my invention is to provide any rotary knitting-machine with an attachment or device which will promptly stop the same whenever the thread breaks or runs off the bobbin, or when any waste or other accumulation occurs on the thread, and thus prevent imperfections in the knitted cloth, and preserve the needles from being broken.

To enable those skilled in the art to make and use my invention, I will proceed to describe its construction and operation.

I attach a horizontal shaft, A, to the front of the frame of the knitting-machine, and on this shaft I place the ratchet-wheel B, and a bevelled gear-wheel D', which last is loose on the shaft, so that it may be moved back laterally thereon, and only revolves with it.

At right angles to this is another short shaft, with a bevelled gear-wheel, D, of same size as D', and which ordinarily works into it, and revolves it and the shaft A, with no other effect; but, as soon as the thread breaks or runs off the bobbin, the anchor or drop-hook b drops on to the ratchet-wheel B, or, in case of accumulations, knots, or kinks occurring on the yarn, the trip-lever F is thrown up and the catch or spur a, on spring C, is permitted to engage the same, and the revolution of the shaft A is stopped, the bevelled gear-wheel D still revolving, while D', which is provided with a screw extending through its hub or collar into a spiral groove in shaft A, slides back on the said shaft a distance equal to the height of its gear or cogs.

Against the back of this wheel D' hangs suspended, on its fulcrum d, the forked knee-lever g, its forked end spanning the collar of D'.

The lateral or retreating motion of D' being thus communicated to lever g, which is connected with or operates on the belt-shifter, stops the knitter instantly whenever the thread breaks or runs off the bobbin, or

any accumulation, kink, or knot occurs that will not pass through the slot in the tripping-lever F.

The belt-shifter is so sensitive that a movement of lever g, to the distance of a sixteenth of an inch, will shift the belt from the driving to the loose pulley, and stop the machine.

The shaft of the bevel-gear wheel D is driven, by being connected with the main or driving-wheel of the cylinder, or head of the knitter.

It frequently happens that yarn runs off the bobbin double or in kinks, in either of which cases the latch or tripping-lever F is lifted, and the spur a, on spring C, allowed to fly up and catch in the ratchet B, and thus stop the machine before any needles can be broken, or any imperfections made in the cloth.

So, too, if the thread breaks at any point outside of the needles, or runs off the bobbin, the slack of the thread e, caused thereby, allows the anchor or drop-hook b to engage the ratchet B, and thus instantly stop the machine, as before described.

The spiral spring e, encircling the shaft A behind the bevelled gear-wheel D', operates to restore said wheel instantly to its place, as often as it is thrown out or back by the teeth of wheel D.

The brace f is attached to the frame of the machine, and is designed to support the lever g.

The anchor or drop-hook b swings or moves freely on the pin or joint h.

Letter e represents the thread running off the bobbin G, up through the slot in lever F, and the hole i in the back spur of drop-hook b, and thence to the needles of the knitter.

While there is no accumulation on the yarn, and it does not break or run off the bobbin, nor double, nor kink, the tension of this thread keeps the hook b up and away from the ratchet B, passing, as it does, through the hole i, in its back-spur, which projects through a mortise in standard E.

What I claim as my invention, and desire to secure by Letters Patent of the United States, is—

The combination of the slotted tripping-lever F, spring C, bevelled gear-wheels D D', ratchet B, drop-hook b, spring e, spur a, and forked lever g, when all are constructed and arranged and operate as, or substantially as and for the purpose herein described.

JOHN KENNEDY.
